POWER UNIT

Emil E. Bohn, Amarillo, Tex.

Application March 25, 1942, Serial No. 436,213

1 Claim. (Cl. 192—4)

This invention relates to a power press of the character including a support for the work and a tool carriage slideable on the support and on which the tool for actuation on the work and its power means is mounted. The primary object of the invention is the provision of an efficient reversible drive between a power means on the support and the carriage whereby the latter may be made to slide in opposite directions to adjust the tool relative to the work and to releasably secure the carriage in various adjusted positions.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a front elevation illustrating a power unit constructed in accordance with my invention.

Figure 2 is a sectional view taken on the line 2—2 of Figure 1.

Figure 3 is a transverse sectional view taken on the line 3—3 of Figure 1.

Figure 4 is a sectional view taken on the line 4—4 of Figure 1.

Figure 5 is a sectional view taken on the line 5—5 of Figure 4.

Figure 6 is a fragmentary sectional view illustrating a train of gears for the drive between a power source and a tool operating shaft.

Figure 7 is a fragmentary sectional view illustrating gears wherein one of the gears includes a ratchet mechanism.

Referring in detail to the drawings, the numeral 5 indicates a vertically arranged supporting frame including a base 6 carrying a work holder 7 and vertical track-forming members 8 connected at their upper ends by a cross member or head 9.

Mounted for vertical sliding movement in opposite directions on the frame 5 is a carriage 10. Carried by the carriage 10 to move therewith and relative thereto, is a tool holder 11. Also carried by the carriage is a power actuated drive mechanism 12 for the tool holder 11.

The carriage 10 includes upper and lower cross members 13 and 14 integrally connected with vertically arranged track-engaging members 15 that slide freely on the track members or portions 8 of the main frame 5 and include slots 16, walls of which have formed thereon rack

teeth 17 engaged by pinions 18 secured to a power driven shaft 19 journaled in bearings provided in the track members 8 of the main frame. The rotation of the shaft 19 in opposite directions will bring about raising and lowering of the carriage on the main frame 5 and the adjustment of the tool carried by the tool holder 11 relative to the work supported by the work holder 7.

The shaft 18 may be rotated in opposite directions by a power mechanism which will be hereinafter described in detail.

Journaled on the carriage 10 between the upper and lower members 13 and 14 by suitable bearings provided therefor is a power shaft 20 on which is secured an eccentric 21 engaged by an eccentric strap 22 forming a part of a connecting rod 23. The eccentric strap 22 is sectional to permit the application and removal of the connecting rod to the eccentric. A wrist pin 24 connects the connecting rod 23 to the tool holder 11, the latter being slidably mounted in the lower member 14 of the carriage. The tool holder 11 may be of any desired construction so that a selected type of tool may be easily and quickly adapted thereto and removed therefrom when desired.

A variable speed transmission 25 of a conventional construction is mounted on the upper member 13 of the carriage 10 and is connected to the shaft 20 by a train of gears 26. A manually operated clutch 27 connects the transmission to a power source 28 mounted on the upper member 13 of the carriage and which may be of any selected type, in this instance shown as being an electric motor.

The variable transmission permits driving of the shaft 20 at different rates of speed and in opposite directions. However, for the successful operation of the tool holder, it is only necessary that the shaft 20 be rotated in one direction. There may be conditions arising when operating on certain kinds of work that make it desirable to rotate the shaft 20 in opposite directions. Therefore, it will be well to have the variable speed transmission of the type which will allow reverse motion to the shaft 20 when desired. The rotation of the eccentric 21 will bring about reciprocation of the tool holder 11 on the carriage and the tool supported thereby relative to the work supported by the work holder 7.

A suitable scale plate 30 is applied to the carriage 10 and a pointer 31 is secured to the main frame 5 and cooperates with the scale plate so that a person or operator of the device may readily determine by measurement the relation

of the tool holder and its tool with respect to the work supported by the work holder 7.

During the use of this power unit it will be necessary, as before stated, to rotate the shaft 19 in opposite directions as well as to secure said shaft against rotation in one direction and also in both directions. Also, it will be desirable to rotate said shaft 19 at different rates of speed and from a power source under direct manual control. Also, it will be desirable during certain phases of operation of this power unit to lower the carriage by gravity. All of these stated operations of the carriage may be easily and quickly carried out through a mechanism which will now be described in detail.

Said mechanism includes a power source 32 mounted on a bracket 33 secured to the main frame 5. The power source 32 is connected to a variable speed transmission 34 by a manually operated clutch 35. The transmission 34 also is manually controlled and the power takeoff gear thereof is indicated by the character 36 located within a suitable gear housing 37 supported by the bracket 33. The power takeoff gear 36 is in continuous mesh with gears 38 and 39, the gear 39 acting as an idler and is journaled on a shaft 40 carried by the gear housing 37. The gear 38 is journaled on a shaft 41 rotatably supported in the gear housing 37. The gear 38 has associated therewith a clutch 42, one of the elements thereof being fixed to the gear 38 while the other element is keyed to the shaft 41.

A gear 43 is in continuous mesh with the gear 39 journaled on a shaft 44 rotatably supported in the gear housing 37. Associated with the gear 43 is a clutch 45, one element thereof being fixed to the gear 43 and the other element being keyed to the shaft 44. A hand controlled lever 46 is provided for the alternate operation of the clutches 42 and 45 and is pivotally mounted on the gear housing 37 and has a neutral position as well as a position for engaging the clutch 45 and another position for the engaging of the clutch 42.

Links 47 are pivoted to the control lever 46 and to bell crank levers 48 pivotally mounted in the gear housing 37. One of the bell crank levers 48 is connected to the keyed element of the clutch 45, while the other bell crank lever is connected to the keyed element of the clutch 42. The power takeoff gear 36 rotates the gears 38 and 43 in the direction, indicated by the arrows in Figure 4 applied to said gears 38 and 43.

A gear 50 is journaled on the shaft 41 and meshes continuously with a gear 51 secured to the shaft 19. A gear 52 is in continuous mesh with the gear 51 and is secured to the shaft 44. The drive between the shaft 44 and the gear 51 may be interrupted by the clutch 45. The gear 50 has formed thereon a brake drum 55 provided with ratchet teeth 54 engaged by spring influenced dogs 53 pivoted on a collar 54' keyed on the shaft 41. The brake drum 55 is journaled on the shaft 41 and the dogs establish a drive between the shaft 41 and the drum. Coactive with the brake drum 55 is a split type brake band 56 pivotally mounted in the gear casing 37, as shown at 57.

The pivoted dogs 53 will act to drive the gear 50 by the shaft 41 in the direction indicated by the arrow applied to said gear 50 in Figure 4. The shaft 41 may be clutched and declutched to the gear 38 which is driven by the power takeoff gear 36. A brake drum 58 is secured to the shaft 44 and coactive therewith is a split type brake

band 59 pivotally mounted in the gear housing 37, as shown at 60. One end of each of the brake bands 56 and 59 has a fixed pivot, as shown at 61. The other ends of the brake bands are pivotally connected to bell crank levers 62. The bell crank levers 62 are mounted for pivotal movement on the pivot 61 and links 64 are pivotally connected thereto. The links 64 are pivotally connected to a control lever 63 pivotally mounted in the gear housing. The brake drums described form brakes for the shafts 41 and 44, which brakes may be alternately operated by the control lever 63, the latter having a neutral position wherein the brake bands both are released from their respective brake drums.

When it is desired to drive the carriage 10 downwardly by power, the clutch 35 is engaged and the transmission 34 placed in a selected gear ratio. The power from the source is then through the clutch 35, transmission 34, gears 36, 38, 50 and 51, it being understood that at this time the clutch 42 is engaged and both brake mechanisms in released position. To raise or elevate the carriage by power, the clutch 42 is disengaged and the clutch 45 engaged. The power will then pass from the gear 36 through the gears 39, 43, 52 and 51 to the shaft 19. It being understood that at this time both brakes are released. To sustain the carriage in an elevated position, the brake band 59 is contracted on the brake drum 58 through the manipulation of the hand lever 63. When it is desired to allow the carriage to move downwardly by gravitation both brakes are released and the clutches 42 and 45 are de-clutched.

To prevent the carriage from moving upwardly under the action of the tool on the work, the band 56 is contracted on the brake drum 55 through the manipulation of the hand lever 63.

After work has been applied to the work holder and it is desired to operate on said work by the tool of the tool carrier 11, the operator may lower the carriage by gravitation to a selected distance to bring the tool in proper relation to the work for operation thereon. The brake band 56 is then contracted on the brake drum 55 so that the carriage will be prevented from moving upwardly under the influence of the tool on the work. The tool is then set in motion or driven by the power source 28 by clutching the clutch 27. The number of strokes made by the tool can be governed easily through the manipulation of said clutch 27.

When it is desired to move the carriage downwardly by power, this can be easily accomplished by clutching the clutch 35, placing the transmission 34 in proper gear so that the power will be to the shaft 19 through the gears 36, 38, 50 and 51. This may be desirable on some forms of work when it is desired to increase the action of the tool on the work. It is again desired to point out that the carriage 10 can be secured against upward movement in any of its adjusted positions by the application of the brake band 56 to the brake drum 55. Also, it will be noted that through the use of the ratchet teeth 54 and dogs 53 the shaft 19 may be driven to raise the carriage without effecting rotation of the shaft 41. Thus it will be seen that during the rotation of the shaft 44 to elevate the carriage, the gear 50 is free to rotate in a direction reverse to that shown by the arrow in Figure 4.

From the foregoing description taken in connection with the accompanying drawings, it will be seen that a very efficient, practical and du-

rable power press has been provided capable of operating various types of tools, such as a punch, die or cutting device. When the device is employed for operating a cutting device the latter may be in the form of shears, one cutting element thereof being connected with the tool holder 11 and the other cutting element being suitably mounted on the work holder.

Further, it will be seen from the disclosure that the device will be extremely simple to control and operate and will be capable of delivering an excessive amount of power to the tool for its operation on the work, still only requiring a small amount of energy to be consumed from the power sources.

While I have shown and described the preferred embodiment of my invention, it will be understood that minor changes in construction, combination and arrangement of parts may be made without departing from the spirit and scope of the invention as claimed.

Having thus described my invention, what I claim is:

5 In a device of the character described, a driven shaft, a housing receiving the shaft, a pair of spaced reversely driven gears journaled in the housing, a gear meshing with the driven gears and secured to one of the shafts, a brake drum secured to one of the driven gears, a ratchet mechanism connected to the other driven gear, a brake drum connected to the ratchet mechanism, brake bands for said drums, oppositely rotated drive gears journaled in the housing, a pair of clutches in said housing and one connecting and disconnecting one of the drive gears to one of the drums and the other clutch connecting and disconnecting the other drive gear to the other drum, a power means for rotating said drive gears, a single operating means for the clutches and extending exteriorly of the housing and supported thereby, and a single operating means for the brake bands extending exteriorly of the housing and supported thereby.

10 15 EMIL E. BOHN.
